UNITED STATES PATENT OFFICE.

HENRY PLATT HALL, OF OLDHAM, ENGLAND.

CARRIAGE FOR SELF-ACTING MULES.

Application filed February 22, 1921. Serial No. 446,983.

To all whom it may concern:

Be it known that I, HENRY PLATT HALL, a subject of the King of the United Kingdom of Great Britain and Ireland, and resident of "Taravon" Werneth, Oldham, in the county of Lancaster, England, have invented new and useful Improvements in Carriages for Self-Acting Mules, of which the following is a specification.

10 This invention relates to carriages for self acting mules whether constructed wholly or in great part of steel or other metal plate or sheet or of wood and consists in devices which in comparison with devices 15 heretofore employed for the like purpose, facilitate the application of carriage bearers on carriages of self acting mules and bearing brackets for tin roller shafts on carriages of self acting mules so constructed.

20 For the attainment of these advantages, the invention consists in devices and constructions to be applied in carriages as aforesaid, which are hereinafter to be described and particularized in the claims, 25 but before reference in detail is made to the several devices and constructions, indication of their general nature will be given by saying the following are comprised in the invention:

30 Steel or other channel bars applied flanges upwards transversely on the bottom of the carriage of a self acting mule or a section thereof and furnished with rising screws for the connection of a carriage 35 bearer; such channel bars which have parts of the flanges made to extend as ears transversely from their ends and are riveted or bolted to angle bars or flanges riveted or otherwise secured or provided on the bottom 40 of the carriage or section;

Such channel bars with ears riveted or bolted to angle bars or flanges riveted or otherwise secured or provided on the bottom of and extending along the carriage or section or sections 45 and extending along it or them;

Such channel bars with ears riveted or bolted to angle bars riveted or otherwise secured or provided on the bottom of and extending along the carriage or section or sections 50 and provided with holes at equal intervals along their length;

Channel bars as aforesaid with holes and communicating slots serving respectively for the passage of the heads and for the 55 passage of the shanks of rising screws;

Channel bars as aforesaid with rising screws attached by spot welding;

A steel or other channel bar applied flanges downwards transversely on the top of the carriage of a self acting mule or a section thereof and made to bear a bearing bracket for the tin roller and a block through or to which is attached a screw for adjusting the bearing bracket lengthwise of the channel bar;

Such a channel bar used for bearing a bearing bracket and a block to receive engagement or attachment of a screw as aforesaid, having parts of the flanges of the channel bar made to furnish at the ends ears at 70 right angles to the bar or in other positions convenient for the attachment of the channel bar;

Such a channel bar used for bearing a bearing bracket and a block to receive engagement or attachment of a screw as aforesaid, having a hole and communicating slot or holes and communicating slots for the passage of the heads and shanks of bolts for securing the bearing bracket for the tin 80 roller or the block or the bracket and block to the channel bar.

This invention is illustrated in the accompanying drawings as applied in a carriage for a self acting mule constructed of steel or other metal plate or sheet in the form of sections constituting when complete a continuous box girder as described in the specification of another application filed on the same day as this and provided with removable rests for the spindle rails or boxes as described in the specification of yet another application filed on the same day as this, Figs. 1 and 2 illustrating the provision on such carriage of means according to this 95 invention for facilitating the application of carriage bearers and Fig. 3 illustrating the provision on such a carriage according to this invention of means for facilitating the application of bearing brackets for tin roller shafts. Fig. 1 is a transverse section through part of the carriage of a self acting mule showing in side elevation part of one of the carriage bearers and the means by which it is secured to the carriage. Fig. 100

2 is a front elevation of some of the parts shown in Fig. 1. Fig. 3 is a transverse section through part of the carriage of a self acting mule showing in side elevation one of the bearing brackets for the tin roller 105. 110

shaft and the means by which the bracket shown is fixed in position.

The same letters of reference are employed to indicate corresponding parts in all the figures.

The mule carriage, parts of which are shown in the several figures, is formed in sections or lengths each of which is formed of a lower steel or other metal plate or sheet 10 bent to form the bottom *a* and to provide upwardly turned flanges *b* *c* forming the front and rear walls of the section and an upper steel or other metal plate or sheet bent to form the top *d* of the section and upwardly turned flanges *e* *f* at the front and rear riveted on the front *b* and back *c* of the section. The sections are connected together end to end by means of angle bars *g* *g*, riveted on the bottoms *a* and flanged brackets *h* *i* riveted on the front and rear and bolted together by bolts passed through the adjacent angle bars *g* *g* and brackets *h* *i* and transverse plates *j* of which one is indicated in Fig. 3 are placed between the opposed sets 20 of angle bars *g* *g* and brackets *h* *i* to stiffen the sections when the nuts upon the connecting bolts are tightened. The connected sections of the carriage form a continuous box girder. 25

The connection of the connected sections to the square of the self acting mule and the completion of the section most remote from the square at the outer ends are effected in any manner convenient. For example angle bars and brackets similar to those shown in Figs. 2 and 3 but preferably extending over greater surfaces of the sections to which they are applied, may be provided upon the ends of the sections to adjoin the square and 30 the sections most remote from the square may be provided at the outer ends directed away from the square with metal plates of appropriate form attached by means of angle bars or brackets. To the front *b* of each section at the upper part is riveted a plate *k* with a flange *l* inclined downwards to the rear to form a rest for the spindle rails or boxes *m* and readily removable for the substitution of another if change in the position of the spindle rails or boxes *m* should be necessary at any time.

According to this invention in order that carriage bearers may be applied to a carriage for a self acting mule constructed as aforesaid, steel or other channel bars with parts of the flanges made to extend as ears transversely from the ends are provided to be applied with the flanges upwards, transversely on the bottoms of the sections of the carriage or carriage bottoms and riveted or advantageously bolted at their ends to angle bars or flanges riveted or otherwise secured to or provided on the bottoms of the sections or carriage and preferably made to extend 40 along them or it so that the channel bars

may be applied at any place requisite in the length of the sections or carriage. In a preferred construction the angle bars or flanges are provided with holes at equal intervals along their length so that the channel bars may be attached at any of a number of places. The channel bars are provided with holes in which "rising screws" of any convenient form, such as screws, bolts or studs, attached to or serving for the attachment of the carriage bearers are secured. Preferably to facilitate application of the rising screws if the holes for them should be accessible from only one side in use, these holes are formed large enough to allow passage of nuts or bolt heads or the like on the rising screws and communicating slots in which the shanks or like parts of the screws may be secured by means of nuts. In an alternative construction rising screws may be fixed in position on the channel bars by spot welding. Channel bars to which rising screws may be attached as aforesaid may also be attached in other ways to mule carriages or sections thereof. 50

In Figs. 1 and 2 *n* *n* are two steel or other channel bars. Each of the channel bars *n* has parts of the flanges made to extend as ears *o* transversely from the ends and one near each end and the other near the front 55 is furnished with a hole and communicating slot to serve respectively for the passage of the head and the passage of the shank of one of the rising screws *p*. A hole is formed in each of the ears *o*. *q* *q* are angle bars or flanges which are formed with holes along their length at equal intervals equal to the distance between the centre lines of the holes in the ears *o* at one end of either of the channel bars *n* and are riveted to the bottom *a* 60 of the section at the front and rear. The channel bars *n* are applied with their flanges upwards on the bottom *a* of the section of the carriage and secured in position by means of rivets passed through holes in the ears *o* and convenient holes in the flanges or angle bars *q*. When the channel bars *n* have been applied to the bottom *a* of the section of the carriage and secured to the flanges or angle bars *q* the heads of the three rising 65 screws *p* are introduced through the holes into the space within the channel bars *n* and the shanks are slipped into the communicating slots and secured therein by means of the nuts *r* and the rising screws *p* are adjusted and secured in position in the carriage bearers *s* in the ordinary manner for the section of the carriage to be supported in the manner requisite by the wheels of the carriage bearer *s*. Other channel bars *n* like 70 the two shown are applied wherever convenient on the sections and elsewhere on the carriage for the connection of carriage bearers.

Channel bars *n* applied with the flanges 75

upwards on the lower surface of a carriage for a self acting mule or sections of such a carriage according to this invention especially when applied along with angle bars or flanges *q* and best of all with angle bars or flanges *q* with holes at equal intervals along their length, afford a very convenient means for the attachment of the rising screws *p*, for the connection of the carriage bearers *s* to the carriage.

According to this invention in order that bearing brackets for a tin roller shaft may be applied on a carriage for a self acting mule constructed as aforesaid, there are provided on the carriage steel or other channel bars with parts of the flanges made to furnish at the ends, ears at right angles to the bars or in other positions convenient for the attachment of the bars. The channel bars are furnished with holes and communicating slots for the passage respectively of the heads and shanks of bolts so that bolts may be inserted if only one face is accessible in use, but if both faces are accessible in use simple holes may serve. The channel bars are applied with flanges downwards transversely on the top of or within the sections or body of the carriage and are riveted or bolted at their ends to sections or the carriage to which they are applied. Each channel bar is made to bear one of the bearing brackets for the tin roller to extend along a carriage and a block through or to which is passed or attached a screw for adjusting the bearing bracket lengthwise of the channel bar, bolts or studs for securing the bearing bracket and block to the channel bar being passed through the holes in it. Brackets secured to the channel bars by means of rivets or by means of bolts passed through the holes, either with communicating slots or simple holes as aforesaid or by other means may be provided to afford screw threaded holes or other appropriate bearing for screws with lock nuts for adjusting and fixing the adjustment of the bearing brackets lengthwise of the channel bars. The channel bars provided in this way for carrying bearing brackets may be attached at any convenient place on the sections or body of a carriage either at the junctions of sections or elsewhere and serve to stiffen the sections to which they are applied.

Channel bars on which bearing brackets may be mounted as aforesaid may also be attached in other ways to mule carriages or sections thereof.

In Fig. 3 *t* is a steel or other channel bar with parts of the flanges made to extend as ears *u* transversely from the ends and in its central part provided with a hole and communicating slot to serve respectively for the passage of the heads of bolts *v* and the passage of the shanks of such bolts *v* and also with a bracket *w* riveted upon it to carry

a set screw *x* furnished with a lock nut. A hole is formed in each of the ears *u*. The channel bar *t* is applied with the flanges downwards on the top *d* of the section of the carriage and the ears *u* are riveted by means of rivets passed through the holes in them and corresponding holes in the upturned flanges *b, e, c, f* of the plates or sheets forming the section so that the channel bar *t* is secured in position. When the tin roller bearing bracket *y* shown which is of ordinary form, is to be applied to the channel bar *t* the heads of the bolts *v* for securing it in position are passed through the hole in the channel bar *t* so that the shanks are passed into the communicating slot and after the tin roller bearing bracket *y* has been adjusted into position by means of the set screw *x* the nuts on the bolts *v* are tightened.

Other channel bars *t* like that shown are applied wherever convenient on the section and elsewhere for the connection of tin roller bearing brackets.

Channel bars applied with the flanges downwards on the top of a carriage for a self acting mule or on sections of such a carriage according to this invention afford a very convenient means for the attachment of tin roller bearing brackets to the carriage.

What I do claim as my invention and desire to secure by Letters Patent is:—

1. A mule carriage, a carriage bearer, transverse channel bars applied flanges upwards to the bottom of the carriage, and rising screws connecting the channel bars to the carriage bearer.

2. A mule carriage, angle bars or flanges secured to its bottom, transverse channel bars applied flanges upwards and secured to said angle bars or flanges, a carriage bearer, and rising screws connecting the channel bars to the carriage bearer.

3. A mule carriage, angle bars or flanges secured to its bottom, transverse channel bars applied flanges upwards and ears extending transversely from the ends of the channel bar flanges and secured to said angle bars or flanges, a carriage bearer, and rising screws connecting the channel bars to the carriage bearer.

4. A mule carriage, angle bars or flanges secured to its bottom, transverse channel bars applied flanges upwards and ears extending transversely from the ends of the channel bar flanges and secured to said angle bars or flanges, a carriage bearer, and rising screws connecting the channel bars to the carriage bearer, said angle bars or flanges having holes at equal intervals along their length for the purpose hereinbefore described.

5. A mule carriage, a carriage bearer, transverse channel bars applied flanges upwards to the bottom of the carriage, and

rising screws connecting the channel bars to the carriage bearer, said channel bars having holes and communicating slots serving respectively for the passage of the heads and for the passage of the shanks of the rising screws as and for the purpose hereinbefore described.

6. A mule carriage, angle bars on its bottom, a channel bar having flanges with parts of said flanges made to extend as ears transversely from the ends, applied flanges upwards transversely on the carriage and riveted to the angle bars and having holes to receive rising screws for connection of a carriage bearer, a carriage bearer, and rising screws connecting the channel bar to the carriage bearer.

7. A mule carriage, angle bars on its bottom with holes at equal intervals through-

out their length, a channel bar having flanges with parts of said flanges made to extend as ears transversely from the ends applied flanges upwards transversely on the carriage and riveted to the angle bars by means of holes therein and having holes to receive rising screws for connection of a carriage bearer; a carriage bearer and rising screws connecting the channel bar to the carriage bearer.

In testimony that I claim the foregoing as my invention, I have signed my name in presence of two witnesses, this eighth day of February, 1921.

HENRY PLATT HALL.

Witnesses:

HOWARD CHEETHAM,

RUTH M. WILSON.
